UNITED STATES PATENT OFFICE.

BERNHARD D. BEIDERHASE, OF NEW YORK, N. Y.

DESIGN FOR SPOON-HANDLES.

Specification forming part of Design No. 5,267, dated September 19, 1871.

To all whom it may concern:

Be it known that I, BERNHARD D. BEIDERHASE, of the city, county, and State of New York, have invented a new and original Design for Spoon-Handle; and I do hereby declare that the following is a full, clear, and exact description thereof, which will enable others skilled in the art to make and use the same, reference being had to the accompanying drawing forming part of this specification.

The nature of my design is fully represented in the accompanying drawing, to which reference is made.

Figure 1 represents a view of the front side of my improved spoon-handle. Fig. 2 is a view of the back or reverse side. Fig. 3 is a cross section of Fig. 1 taken on the line *x x*.

I claim as my invention—

The design for a spoon-handle, as shown.

BERNHARD D. BEIDERHASE.
